UNITED STATES PATENT OFFICE.

HARRY C. GAMMETER, OF COLLINWOOD, OHIO, ASSIGNOR TO THE AMERICAN MULTIGRAPH COMPANY, OF CLEVELAND, OHIO, A CORPORATION OF OHIO.

RIBBON-FEEDING MECHANISM.

997,287.

Specification of Letters Patent. Patented July 11, 1911.

Application filed December 16, 1907. Serial No. 406,678.

To all whom it may concern:

Be it known that I, HARRY C. GAMMETER, residing at Collinwood, in the county of Cuyahoga and State of Ohio, have invented 5 a certain new and useful Improvement in Ribbon-Feeding Mechanism, of which the following is a full, clear, and exact description, reference being had to the accompanying drawings.

10 The object of this invention is to effect an efficient combination with a rotary printer, or a printing mechanism which carries a page form, using an inking ribbon, of mechanism for feeding such ribbon and for 15 automatically reversing the direction of the feed.

My mechanism is particularly well adapted for embodiment in a printing machine having a rotary drum carrying two spools 20 on which the ends of the ribbon are wound. The feeding mechanism is carried partly by such drum and partly by a stationary member, so that the rotation of the drum automatically causes the feeding of the ribbon, 25 and when either spool becomes empty the mechanism is automatically shifted to drive the other spool.

The invention consists in the means by which this result is accomplished. This is 30 illustrated in the embodiment hereinafter described and is summarized in the claims.

My divisional application No. 418,657, filed March 2, 1908, covers the ribbon feeding and reversing mechanism of this application in its broad aspect and irrespective of its combination with a printing mechanism. The present patent is concerned with the combination of the ribbon feeding and reversing mechanism with a printing mechanism, as above referred to.

In the drawings, Figure 1 is a front elevation of a rotary printing machine which may embody my feeding mechanism; Fig. 2 is an enlarged view of the ribbon spools with 45 their supports and holding springs; Fig. 3 is a vertical section through the right hand frame member of the machine and the adjacent end of the drum; Fig. 4 is an elevation of the right hand end member of the 50 drum which carries the feeding mechanism, this view being taken looking from the interior of the drum; Fig. 5 is an outside end view of the drum sectioned through the stationary eccentric on the frame member; 55 Figs. 6 and 7 are portions of similar views in

different positions. The remaining figures are perspectives of different members of the feeding mechanism.

Referring to the parts by reference numerals, 20 represents the frame of the machine which is shown as having a pair of vertical end plates 21 and 22. Mounted in these plates is the shaft 23 which carries the printing drum, the drum having spider-like end members 24 and 25 and having a partial cylindrical surface 26 on which are longitudinal rails 27 forming undercut channels adapted to carry rows of individual grooved type. A crank 28 furnishes means for rotating the drum. Beneath the drum is a rotary platen 30 connected with the drum by gears 31 and 32.

35 and 36 represent the ribbon spools which occupy a recess in the drum. The ends of the ribbon are secured to these spools, for example, by means of trough-shaped clamps 38 springing into slots in the spools. The ribbon passes from one spool around the surface of the drum and over the type to the other spool. Accordingly, if the drum be rotated by the crank and paper be fed to the contacting line of the drum and platen, the same will be printed by successive lines of type through the ribbon. The type may well have a face similar to 80 typewriter type, in which case the rolling contact through the ribbon produces an almost exact imitation of typewritten work, the irregularities resulting from the type being somewhat loosely held on the drum heightening this effect.

To present a fresh face to the type for successive impressions, I provide mechanism to gradually rotate either ribbon spool. As 85 shown, this mechanism includes a pair of ratchet wheels 40 and 41 adapted to be connected with the respective spools by lugs 42 engaging openings in the spool heads 39. Fig. 8 illustrates such ratchet wheel 40. The spools are pressed toward the ratchets by a spring 33 (Fig. 2) forcing inward the pins 34 of which the spools bear at that end. A stationary eccentric 44, formed as a boss on the inner side of the frame member 22, operates intermediate mechanism carried by the end member 24 of the drum and traveling around with the drum and reciprocated in and out radially by such eccentric to operate the corresponding spool. Such mechanism 90 is covered broadly in my copending application.

cation No. 240,167. The present embodiment also has features in the mechanism between the eccentric and the ratchets covered by my copending application No. 298,122. 5 The present invention is an improvement on each of these prior inventions, in providing an effective and certain mechanism for changing the direction of drive as soon as either spool becomes empty. I will now 10 proceed to describe the mechanism which effects the ribbon drive and allows this automatic reversal.

45 indicates an eccentric strap surrounding the stationary eccentric 44. At its outer 15 end this strap extends around a pin 46 projecting from a bar 47, the lower end of which yokes around the shaft 23 having a parallel sided elongated opening 48 which engages a guiding bushing 49 on the shaft. 20 Fig. 9 shows the eccentric strap and Fig. 10 the bar. Near its outer end this bar 47 carries a block 51 slidably engaging a radial pin 52 carried by the end member 24 of the drum, the result being that this bar is reciprocated radially as the drum rotates. 25

Pivoted to the bar 47 by the pin 55 is a plate 56 in the form shown in Fig. 14, the pin passing through an opening 53 in the plate. Pivoted to this plate on the opposite sides of its pivot are two pawls 57 and 30 58 in the form shown in Fig. 13. The lower ends of these pawls are given a tendency to move toward each other by a spring 60 connected to such lower ends. Mounted on 35 the pivot pins 61 of these pawls are short rock arms 63, of the form shown in Fig. 12, each rock arm having a lug adapted to engage the outer side of the respective pawl 57 or 58. These two rock arms are constrained toward each other by a spring 65 40 which is materially stronger than the spring 60. The upper end of the bar 47 is bent parallel therewith, after the manner of an inverted U, as shown at 67 in Fig. 10. Between this bent over portion and the body of 45 the bar is a roller 68 (shown detached in Fig. 11) which is adapted to lie in either of two recesses 70 in the plate 56, the roller being constrained inwardly radially by 50 means of a spring 72, anchored on the pin 55 and connected at its outer end with a hook 73 passing through a slot 74 in the bent over end 67 of the bar 47 and passing into a central opening in the roller 68.

55 The operation of the above described construction is as follows: When the plate 56 is in either extreme position, it is normally held by the roller 68 and the spring 72, and accordingly reciprocates as one with the bar 47, this reciprocation causing the corresponding pawl 57 or 58 to engage the teeth of the corresponding ratchet and feed the same when the bar moves inward. The spring 65 acting on the rock arms 63 prevents the pawls normally passing outwardly

beyond the limits provided by the lugs 64, so that the unengaged pawl is normally idle. The engaged pawl may swing inwardly, as the convexity of the ratchet moves it away from the lug, the spring 60 allowing this result. As shown in Figs. 4 and 5, the pawl 57 is in position to engage the ratchet 40. If, however, the roller 68 were in engagement with the other notch 70, the member 56 would be positioned so that the pawl 58 would be in position to engage the ratchet 41, the other pawl being idle. A projecting lip 75 at the upper end of the plate 56 furnishes a handle by which it may be shifted by the operator's fingers into either position to set the direction of the drive as desired. The peculiar advantage, however, of my driving mechanism is its automatically reversing feature. This operates as follows: When either ribbon spool becomes full, as, for example, the spool 35 connected with the ratchet 40, the pawl operating therewith, for example 57, is retarded on its inward stroke by reason of the stretched ribbon (held by the empty spool) preventing the ratchet rotating. This retardation anchors, as it were, the pivot 61 of the pawl so that on the continued movement of the bar and plate 56, this plate swings about such pin as a pivot and thereby passes over to its other extreme position, the roller 68 being forced outwardly slightly and passing into the other depression 70. The described movement, however, cannot take place until the driving pawl, as 57, has a firm hold on its ratchet and is held thereto by the back lash of the ratchet teeth and the pawl nose. Accordingly, when the plate 56 swings over to the other extreme position, the engaged pawl, as 57, does not immediately swing with it but retains its engagement with the former ratchet wheel, the spring 65 expanding to allow such movement. The other pawl, as 58, comes into engagement with its wheel, and, accordingly, the driving mechanism is connected with both wheels, and the rest of the inward movement winds in both spools and tightens the ribbon. This tightening movement is only for a slight distance and is sufficient to take up any slack in the ribbon, so that the new ratchet is in position to immediately wind the ribbon. Now, when the mechanism moves outwardly, the former pawl, as 57, releases its hold on the ratchet, and then, by reason of the contraction of the spring 65, swings backwardly into idle position, wherefore the continued movement operates the newly engaged ratchet only. It is to be understood that the effective driving movement of the mechanism takes place while the recess in which the spools are mounted is moving past the platen. The eccentric 44 extends in such direction that while the type portion of the drum is moving past the platen, the driving mechanism

is either moving outwardly or moving inwardly but beyond the ratchets. The outer movement occupies half the rotation and the idle inward movement substantially a quarter of the rotation so that the effective inward movement, which is the last half of the total inward movement, is substantially for a quarter rotation.

Figs. 5, 6 and 7 illustrate the position of the drum when the automatic shifting may take place, these views being taken looking at the end of the drum from the right hand with the parts traveling in the direction of the arrows. It will be seen that in Fig. 6, 10 the driving mechanism is moving outwardly, then after it leaves the upper left hand portion of the circle it begins to move inwardly, the actual engagement taking place as the mechanism is leaving the lower left hand 15 portion of the circle. If on such engagement one of the spools is empty, the driving mechanism will come into the position shown in Fig. 6, where the pawls engage both ratchets and where the ribbon is pulled from both 20 directions. This pull will continue until the driving mechanism has entered the lower right hand portion of the circle. Then, as the mechanism is moving upwardly, it moves outwardly so that, as it comes into 25 the position shown in Fig. 7 in the upper right hand portion of the circle, the former pawl releases its hold on the former ratchet, and the mechanism is thus completely reversed, ready for successive subsequent feeding 30 on the new ratchet.

I claim:

1. The combination with a movable printing mechanism adapted to carry a page form and print through a ribbon, of a pair of ribbon spools carried by said movable mechanism, a pair of independent driving members therefor, a member mounted on a movable pivot and carrying the driving members, means for moving such pivot, and spring 40 detent mechanism tending to hold such carrying member in either of two active positions, whereby there may be automatic shifting of the drive from one spool to the other.

2. The combination with a movable printing mechanism adapted to carry a page form and print through a ribbon, of a pair of ribbon spools carried by said movable mechanism, a pair of independently pivoted driving pawls therefor, and a member on which 50 the pawls are pivoted, the said member being itself pivoted on an axis parallel with the pawl pivots and with its coöperating parts constituting an automatic mechanism for shifting the drive from one spool to the other.

3. The combination with a movable printing mechanism adapted to carry a page form and print through a ribbon, of a pair of wheels carried by said movable mechanism, a pair of pawls for driving the same, a driv-

ing mechanism carrying said pawls by means of a member mounted on a movable pivot and means for automatically changing the presentation of the driving mechanism to present either pawl to the corresponding wheel.

4. The combination with a movable printing mechanism adapted to carry a page form and print through a ribbon, of a pair of ratchet wheels carried by said movable mechanism, a pair of independently pivoted pawls for driving the same, and means for automatically changing the presentation of the driving mechanism by mutually shifting the pawl pivots in the planes of the ratchet wheels to present either pawl to the corresponding wheel.

5. The combination with a printing mechanism adapted to carry a page form and print through a ribbon, of a pair of wheels, a pair of pawls for driving the same, and means for automatically changing the presentation of the driving mechanism to present either pawl to the corresponding wheel, said means during such change causing both pawls to engage both wheels.

6. The combination with a movable printing mechanism adapted to carry a page form and print through a ribbon, of a pair of ribbon spools carried by said movable mechanism, a pair of independently pivoted pawls for driving them, means for normally holding either pawl in position to operate the corresponding spool, and means operated automatically by the anchoring of a pawl consequent upon a spool becoming empty to shift the driving mechanism to bring the other pawl into cooperation with the empty spool.

7. The combination with a printing mechanism adapted to carry a page form and print through a ribbon, of a pair of spools, a pair of independently pivoted driving pawls, and a pivoted member on which said pawls are mounted on opposite sides of its pivot, whereby the retardation of either pawl may shift the member to bring the other pawl into engagement with the other wheel.

8. The combination with a movable printing mechanism adapted to carry a page form and print through a ribbon, of a pair of spools carried by said movable mechanism, a pair of independently pivoted driving pawls, a pivoted member on which said pawls are mounted on opposite sides of its pivot, the pivots of said member and said pawls being all substantially parallel, and a spring detent for normally holding said member in either extreme position.

9. The combination with a printing mechanism adapted to carry a page form and print through a ribbon, of a pair of wheels, a pair of pawls adapted to engage their respective wheels, a pivoted member carrying

said pawls and adapted to be held with either pawl in position to coöperate with its corresponding wheel, the stoppage of either pawl causing the member to shift on its pivot to bring the other pawl into engagement with the other wheel.

10. The combination with a printing mechanism adapted to carry a page form and print through a ribbon, of a pair of 10 wheels, a pair of pawls adapted to engage their respective wheels, and a movable member carrying said pawls and adapted to be held with either pawl in position to coöperate with its corresponding wheel, said 15 member being formed to allow both pawls to simultaneously engage with both wheels.

11. The combination with a printing mechanism adapted to carry a page form and print through a ribbon, of a pair of 20 wheels, a reciprocating member, a bodily movable member pivotally carried thereby, a pair of pawls pivotally mounted on said pivoted member on opposite sides of its pivot, said pawls being adapted to engage 25 said wheels respectively.

12. The combination with a printing mechanism adapted to carry a page form and print through a ribbon, of a pair of wheels, a reciprocating member, a bodily 30 movable plate pivoted thereto, and a pair of pawls pivotally mounted on said plate, said pawls being adapted to engage said wheels respectively.

13. The combination with a printing mechanism adapted to carry a page form and print through a ribbon, of a pair of 35 wheels, a reciprocating member, a bodily movable pivoted member carried thereby, a pair of pawls pivotally mounted on said 40 pivoted member, said pawls being adapted to engage said wheels respectively, and spring mechanism adapted to hold the idle pawl in idle position but allowing it to be moved against the action of the spring to 45 engage the corresponding wheel.

14. The combination with a printing mechanism adapted to print by rolling contact through an inking ribbon, of a pair of ratchet wheels, a pair of pawls, means giving 50 said pawls a tendency to move outwardly, movable stops limiting the outward movement, and means holding said stops in normal position.

15. The combination with a printing mechanism adapted to print by rolling contact through an inking ribbon, of a pair of 55 ratchet wheels, a pair of pivoted pawls, a spring connecting said pawls and giving them a tendency to move outwardly, stops 60 limiting the outward movement, and a spring holding said stops in normal position.

16. The combination with a printing mechanism adapted to print by rolling contact through an inking ribbon, of a pair of 65 ratchet wheels adapted to be connected with

a pair of ribbon spools, a reciprocating member, a bodily movable pivoted member thereon, a pair of pawls pivotally mounted on said pivoted member and adapted to engage the respective ratchet wheels, and means tending to move said pawls outwardly.

17. The combination with a printing mechanism adapted to print by rolling contact through an inking ribbon, of a pair of 75 ratchet wheels adapted to be connected with a pair of ribbon spools, a reciprocating member, a pivoted member thereon, a pair of pawls pivotally mounted on said pivoted member on opposite sides of its pivot and 80 adapted to engage the respective ratchet wheels, and a spring tending to move said pawls outwardly.

18. The combination with a printing mechanism adapted to carry a page form 85 and print through a ribbon, of a reciprocating member, a pivoted member mounted thereon, a pair of pawls pivotally carried by said pivoted member, means tending to force said pawls outwardly, and spring controlled restraining means elastically limiting the outward movement of the pawls with reference to the member on which they 90 are pivoted.

19. The combination with a printing 95 mechanism adapted to print by rolling contact through an inking ribbon, of a pair of ratchet wheels adapted to be connected with a pair of ribbon spools, a reciprocating member, a pivoted member thereon, a pair 100 of pawls pivotally mounted on said pivoted member and adapted to engage the respective ratchet wheels, and a spring tending to move said pawls outwardly, and a pair of rock arms pivotally carried also by said pivoted member, said rock arms having lugs providing stops for the pawls, and a spring connecting said rock arms, said spring being stronger than the spring connecting the pawls.

20. The combination with a printing mechanism adapted to carry a page form and print through a ribbon, of a reciprocating member, a pivoted member mounted thereon, means mounted on one of said members and adapted to occupy either of two recesses in the other member, a spring for constraining said means, and a pair of pawls pivotally carried by said pivoted member.

21. The combination with a printing mechanism adapted to carry a page form and print through a ribbon, of a pair of ratchet wheels, a reciprocating member, a pivoted member mounted thereon, a roller guided by the reciprocating member adapted to occupy either of two recesses in the pivoted member, a spring for constraining said roller, and a pair of pawls pivotally carried by said pivoted member and adapted to engage said wheels respectively.

22. The combination with a printing mechanism adapted to carry a page form and print through a ribbon, of a reciprocating member, a pivoted member mounted thereon, 5 a roller guided by the reciprocating member adapted to occupy either of two recesses in the pivoted member, a spring for constraining said roller, and a pair of pawls pivotally carried by said pivoted member, 10 means tending to force said pawls outwardly, the spring controlled restraining means for the pawls.

23. The combination of a rotary printing drum, a pair of spools, a pair of independently pivoted pawls mounted therein, means 15 for normally holding either pawl in position to operate the corresponding spool, and means operated automatically by a spool becoming non-rotatable to shift the driving 20 mechanism to bring the other pawl into co-operation with the other spool.

24. The combination of a rotary printing drum, a pair of spools mounted therein, a pair of independently pivoted driving pawls, 25 and a pivoted member on which said pawls are mounted on opposite sides of its pivot, whereby the retardation of either pawl may shift the member to bring the other pawl into engagement with the other wheel.

30 25. The combination of a rotary printing drum, a pair of wheels mounted therein, a pair of pawls adapted to engage their respective wheels, a pivoted member carrying said pawls and adapted to be held with 35 either pawl in position to coöperate with its corresponding wheel, the stoppage of either pawl causing the member to shift on its pivot to bring the other pawl into engagement with the other wheel.

40 26. The combination of a rotary printing drum, of a pair of wheels mounted therein, a pair of pawls adapted to engage their respective wheels, and a movable member carrying said pawls and adapted to be held 45 with either pawl in position to coöperate with its corresponding wheel, said member being formed to allow both pawls to simultaneously engage with both wheels.

27. The combination of a rotary printing 50 drum, of a pair of wheels mounted therein, a reciprocating member, a pivoted member carried thereby, a pair of pawls pivotally mounted on said pivoted member, said pawls being adapted to engage said wheels respectively, spring mechanism adapted to hold the idle pawl in idle position but allowing it to be moved against the action of the spring to engage the corresponding wheel, and means for reciprocating said reciprocating member.

60 28. The combination of a rotary printing drum, a pair of ratchet wheels mounted therein, a pair of pivoted pawls, a spring connecting said pawls and giving them a 65 tendency to move outwardly, stops limiting

the outward movement, and a spring holding said stops in normal position.

29. The combination of a rotary printing drum, a pair of ratchet wheels mounted therein and adapted to be connected with a 70 pair of ribbon spools, a reciprocating member, a pivoted member thereon, a pair of pawls pivotally mounted on said pivoted member on opposite sides of its pivot and adapted to engage the respective ratchet wheels, a spring tending to move said pawls outwardly, and a stationary eccentric for operating said reciprocating member. 75

30. The combination of a rotary printing drum, a reciprocating member mounted 80 therein, a pivoted member mounted thereon, a pair of pawls pivotally carried by said pivoted member, means tending to force said pawls outwardly, and spring controlled restraining means for the pawls. 85

31. The combination of a rotary printing drum having a recess, a pair of ratchet wheels mounted therein and adapted to be connected with a pair of ribbon spools, a reciprocating member, a pivoted member thereon, a pair of pawls pivotally mounted on said pivoted member and adapted to engage the respective ratchet wheels, a spring tending to move said pawls outwardly, a 90 pair of rock arms pivotally carried also by said pivoted member, said rock arms having lugs providing stops for the pawls, a spring connecting said rock arms, said spring being stronger than the spring connecting the pawls, a platen, and means for moving said reciprocating member inwardly while the recess in the drum is moving past the platen. 95

32. The combination of a rotary printing drum, a reciprocating member mounted 100 therein, a pivoted member mounted thereon, a roller guided by one of said members and adapted to occupy either of two recesses in the other member, a spring for constraining said roller, a pair of pawls pivotally carried by said pivoted member, and a stationary eccentric for operating said reciprocating member. 110

33. The combination of a rotary printing drum, a pair of ratchet wheels mounted 115 therein, a reciprocating member, a pivoted member mounted thereon, a roller guided by the reciprocating member adapted to occupy either of two recesses in the pivoted member, a spring for constraining said roller, a pair of pawls pivotally carried by said pivoted member and adapted to engage said wheels respectively, and means for reciprocating said reciprocating member. 120

34. The combination of a rotary printing drum, a reciprocating member mounted 125 therein, a pivoted member mounted thereon, a roller guided by the reciprocating member adapted to occupy either of two recesses in the pivoted member, a spring for constraining said roller, a pair of pawls pivotally car- 130

ried by said pivoted member, means tending to force said pawls outwardly, a spring controlled restraining means for the pawls, and means for reciprocating said reciprocating member.

35. The combination of a rotary drum having a recess, a pair of ribbon spools mounted therein, a ratchet wheel for each spool, a radially reciprocating bar carried 10 by the drum, a member pivotally mounted on said bar, a pair of pawls pivotally mounted on said member, a platen, and mechanism for moving said bar inwardly as the recess moves past the platen.

15 36. The combination with a printing mechanism adapted to carry a page form and print through a ribbon, of spools for carrying the ribbon, wheels for rotating said spools, a reciprocating member, a bodily 20 movable member pivoted thereto, a pair of pawls pivoted to the pivoted member, means for swinging said pawls on their pivots, and elastic means for limiting such movement of the pawls.

25 37. The combination of printing mechanism adapted to carry a page form and print through a ribbon, of spools for carrying the ribbon, wheels for rotating said spools, a pivoted member, a pair of pawls pivoted to the 30 pivoted member, spring means for swinging said pawls on their pivots, and elastic means for limiting such movement of the pawls.

38. The combination with a printing mechanism adapted to carry a page form 35 and print through a ribbon, of spools for carrying the ribbon, wheels for rotating said spools, a pair of pivoted pawls, spring means for swinging said pawls on their pivots, and elastic means for limiting such 40 movement of the pawls.

39. The combination of a rotary printing drum, a pair of pivoted pawls carried thereby, means for swinging said pawls on their pivots, elastic means for limiting such movement of the pawls, and ribbon feeding mechanism operated by said pawls.

40. The combination of a rotary printing drum, a pivoted member carried thereby, a pair of pawls pivoted to the pivoted mem-

ber, spring means for swinging said pawls 50 on their pivots, elastically held means for limiting such movement of the pawls, and ribbon feeding mechanism operated by said pawls.

41. The combination of a rotary printing 55 drum, a reciprocating member carried thereby, a member pivoted to the reciprocating member, a pair of pawls pivoted to the pivoted member, means for swinging said pawls on their pivots, elastic means for limiting 60 such movement of the pawls, and ribbon feeding mechanism operated by said pawls.

42. The combination of a rotary printing drum, a stationary eccentric surrounding the axis of the drum, an eccentric strap 65 surrounding the eccentric, a reciprocating bar mounted on the drum and connected with said strap, a plate pivoted to said bar, a pair of pawls pivoted to said plate, spring means tending to swing said pawls on their pivots, 70 elastic means for limiting such movement of the pawls, and ribbon feeding mechanism operated by said pawls.

43. The combination with a printing mechanism adapted to carry a page form 75 and print through a ribbon, of a pair of ratchet wheels, a pair of pawls, means for giving said pawls a tendency to move toward the ratchet wheels, movable means for limiting such movement, and elastic means for 80 restraining said movable means.

44. The combination with a printing mechanism adapted to carry a page form 85 and print through a ribbon, of a pair of ribbon carrying spools and a pair of ratchet 90 wheels therefor respectively, a pair of pawls for driving the respective ratchets, spring means for giving said pawls a tendency to move toward the ratchets, movable stops for limiting such movement, and spring means for yieldingly holding said stops in normal 90 position.

In testimony whereof, I hereunto affix my signature in the presence of two witnesses.

HARRY C. GAMMETER.
